Primary Examiner — George D. Kirschbaum

(57) **CLAIM**

The ornamental design for a pressure measuring device, as shown and described.

DESCRIPTION

1. Pressure measuring device

1.1 is a right side view.

1.2 is a left side view.

1.3 is a front view.

1.4 is a back view.

1.5 is a top perspective view.

1.6 is a top view.

1.7 is a second top perspective view.

1.8 is a front view.

1.9 is a right side view.

1.10 is a back view.

1.11 is a left side view.

1.12 is a top perspective view.

1.13 is a second top perspective view.

1.14 is an enlarged view.

1.15 is an enlarged view.

1.16 is an enlarged view.

1.17 is an enlarged view.

1.18 is a top perspective enlarged view.

1.19 is a second top perspective enlarged view.

1.20 top enlarged view.

1.21 is a bottom enlarged view.
